UNITED STATES PATENT OFFICE.

DAVID SHERWOOD KENNEDY, OF BROOKLYN, NEW YORK, ASSIGNOR TO MERGEN-
THALER LINOTYPE COMPANY, A CORPORATION OF NEW YORK.

TYPOGRAPHICAL COMPOSING-MACHINE.

1,081,753.

Specification of Letters Patent. Patented Dec. 16, 1913.

Application filed April 3, 1912. Serial No. 688,122.

To all whom it may concern:

Be it known that I, DAVID SHERWOOD KENNEDY, a citizen of the United States, and a resident of Brooklyn, county of Kings, and State of New York, have invented a new and useful Improvement in Typographical Composing-Machines, of which the following is a specification.

My invention relates to typographical composing machines, such for instance as linotype machines of the general organization represented in Letters Patent of the United States to John R. Rogers, No. 848,771, dated April 2, 1907, and No. 930,693, dated August 10, 1909, wherein is employed a series of superposed magazines, each containing a font of matrices, and arranged so as to deliver the matrices from the selected magazine over an intervening bridge and through vertical channels, to the assembling devices, and wherein the matrices are subsequently presented to the casting mechanism, where they form type characters on bars or slugs cast in a slotted mold. In these machines each magazine is provided with a series of escapements to control the delivery of the matrices therefrom, and the several series of escapements are actuated by a single set of reeds mounted in a vertically sliding sash-frame, which is movable upward and downward at the will of the operator, so as to engage the reeds with the escapements of one magazine or another as demanded. This single set of reeds is connected in its different positions so as to be actuated by a set of main reeds mounted in the main frame, which are in turn operated through suitable connections from the keyboard in the ordinary manner. In order to engage and disengage the single set of reeds with one or the other of the several series of escapements, the vertically sliding sash-frame is provided with a secondary frame movable horizontally therein, the outward movement of which disengages the reeds from the escapements of the operative magazine before the sash-frame is shifted vertically, and the inward movement of which engages the reeds with the escapements of another magazine in the new position of the sash-frame, these respective outward and inward movements of the frame simultaneously disengaging and engaging the reeds with the keyboard connections.

It sometimes happens from various causes, such for instance as unequal wear, that the sash-frame will not aline truly but drops slightly below its proper level, so that in operative position the bridge, as well as the actuating reeds, will not register exactly with the selected magazine and its escapements. I therefore provide means for interlocking the sash-frame directly with the individual magazine and thereby insure alinement of the parts carried thereby with the magazine. To this end I preferably employ means connected to the secondary frame, and sharing its inward and outward movements, which means engage directly with the selected magazine, or other suitable stationary member, when the parts are in operative relation. Preferably also these sustaining means are connected to the sash-frame so as to permit their movement relatively thereto, although at all times supporting it and giving it additional rigidity.

As heretofore constructed, the alinement of the parts has been dependent upon the connections between a number of intermediate devices, where there may be considerable play or lost motion. By directly supporting the sash-frame and its secondary frame according to my invention, I not only secure direct and positive registration, but in addition thereto impart strength and rigidity to the entire structure.

In the accompanying drawing I have shown my invention in preferred form and by way of example, and as applied to the special style of machine illustrated in the before-mentioned patents, but obviously many changes and variations may be made therein and in its mode of application without departure from its spirit, and I desire it to be distinctly understood that I do not limit myself to any specific form or embodiment except in so far as such limitations are specified in the claims.

Referring to the drawing: Figure 1 is a detached rear view of the movable frames and connected parts, having my invention applied thereto, partly broken away and partly in section; and Fig. 2 is a transverse vertical section through the lower portion of the magazines, the movable frames, etc.

The general structure and organization is or may be substantially like that illustrated in the before-mentioned Letters Patent, No. 930,693, wherein a series of superposed in-

clined magazines B is mounted in the frame. Each of the magazines is designed to carry a font of matrices C, and is provided at its underside with a series of pivoted escapements E to control the release of the matrices therefrom. The vertically movable sash-frame F carries a single set of reeds G designed to connect with and actuate one series of escapements at a time. These reeds are supported and guided by the cross-bars H, which are mounted in the sash-frame F and movable horizontally with relation thereto. The inward and outward movements of the bars H engage the reeds G with and disengage them from the chosen series of escapements E, while the vertical movement of the sash-frame F shifts the reeds into position to be engaged with the escapements of another magazine as required. When the machine is adjusted for operation, the sash-frame remains at rest and the reeds G have a limited vertical motion, which motion is imparted by the pivoted levers M engaging notches g therein. The levers M are operated by the vertical reeds N which are actuated in the usual manner from the keyboard not herein shown. As the levers M are fixed in position, and the reeds G are adjustable upward and downward from one magazine to another, it follows that the levers must engage the reeds at a plurality of points according to the height to which the latter are adjusted, and to this end each reed is provided with several notches g, one for each magazine.

Preparatory to shifting the sash-frame and the reeds carried thereby upward and downward, the reeds are first disengaged from the escapements, and this is effected by moving the guide bars H outward in the frame F, as already stated. To this end, the bars H are provided with horizontal racks engaged by pinions h¹ on horizontal shafts in the frame F, which pinions are in turn actuated by a vertically sliding rack bar h² mounted in the frame F, and operated by the pinion h⁴. After the disengagement of the reeds G from the escapements E and the levers M, the frame F and the reeds are shifted to their new position, and to this end the frame is provided with vertical racks f³ engaged by pinions f² mounted on the shaft h⁵. The pinion h⁴, and the shaft h⁵ carrying the pinions f², are actuated through intermediate connections from the hand levers h⁹ and h¹¹. A bridge or supporting plate L is also mounted near the top of the sash-frame F and is adapted to receive the matrices from the particular magazine in use and to guide them into the channels of the face plate I, which directs them downward to the usual assembling devices. All of the parts and operations so far described are or may be substantially the same as those disclosed in the Letters Patent No.

930,693, wherein the corresponding parts are designated by substantially the same characters of reference.

Turning now to the particular feature of my present invention, namely, the additional means for supporting and registering the parts in operative position, I provide the upright bars O, preferably disposed in vertical position and attached to the guide bars H, in such manner that the two sets of bars constitute in effect a connected frame. The upper extremities of the bars O are formed with projecting portions or hooks O¹ designed to enter and engage the notches P formed in the rigid side bars of the magazines B, or any other suitable or conveniently located parts of the machine. The lower extremities of the bars O are similarly provided with projecting portions or hooks O² to engage the lower cross bar of the sash-frame F, these projecting portions O² being of sufficient extent to engage at all times with the said cross bar, notwithstanding the horizontal movement of the bars O with relation thereto.

The operation of my improved locking means will now be clearly understood. The outward movement of the frame, constituted by the guide bars H and the locking bars O, disengages the reeds G from the levers M and the escapements E of the magazine B in operative position, and simultaneously disengages the hooks O¹ from the notches P. The extended formation of the portions O² of the locking bars O permits their movement with relation to the frame F without their disengagement therefrom. The frame F is now shifted vertically to bring the bridge L into relation to another magazine B, and the reeds G into relation to the escapements E thereof, after which the guides H and reeds G are moved inwardly to engage the latter with the levers M and the escapements E of the new magazine, and simultaneously to engage the hooks O¹ with the notches P thereof. Due to this construction and arrangement, it will be seen that the alinement and registration of the several parts are insured, and that the frame F and the devices carried thereby are firmly and rigidly supported in proper relation to the respective magazines, and this without dependence upon their connection or relation to other intermediate parts.

As previously stated, many variations and modifications will suggest themselves to those skilled in the art without departure from the scope of the invention.

Having thus described my invention, its construction and mode of operation, what I claim and desire to secure by Letters Patent of the United States is as follows:

1. In a typographical machine, the combination of a plurality of magazines, a series of escapements for each magazine, a single

- set of actuating devices for the several series of escapements, means to shift the said actuating devices into operative relation to any selected series of escapements, and supplemental means to secure their registration and support them in alinement therewith. 5
2. In a typographical machine, the combination of a plurality of overlying magazines each provided with a series of escapements, and escapement actuating devices adjustable at will to directly engage the escapements of any magazine, together with supplemental means to insure their registration and support them in alinement therewith. 10
3. In a typographical machine, the combination of a series of superposed magazines, a raceway to receive matrices from all the magazines, and an intermediate adjustable bridge or support to carry the matrices from one magazine at a time to the raceway, together with supplemental means to insure the registration of the bridge with the selected magazine and to support it in alinement therewith. 15
4. In a typographical machine, the combination of a plurality of superposed magazines each having a series of escapements, a raceway to receive the matrices, an intermediate adjustable bridge to carry the matrices from one magazine at a time to the raceway, a single set of actuating devices for the escapements, means for shifting the bridge and the escapement actuating devices into engagement with the selected magazine, and supplemental means to insure the proper registration of the bridge and escapement actuating devices in relation to the selected magazine and to support them in alinement therewith. 20
5. In a typographical machine, the combination of a series of superposed magazines each provided with suitable escapements, a raceway to receive the matrices from all the magazines, a bridge to support the matrices from one magazine at a time to the raceway, actuating devices for the escapements, and an adjustable frame carrying the bridge and escapement actuating devices and provided with supplemental means to insure their proper registration and support them in alinement in relation to the selected magazine. 25
6. In a typographical machine, the combination of a plurality of magazines, a raceway to receive the matrices from all of the magazines, a bridge to carry the matrices from one magazine at a time to the raceway, and a vertically adjustable frame carrying the bridge and provided with supplemental locking means to engage the selected magazine to insure the registration of the bridge and support it in alinement therewith. 30
7. In a typographical machine, the combination of a plurality of magazines each provided with suitable escapements, escape- 35
- ment actuating devices, and an adjustable frame carrying the said escapement actuating devices and provided with supplemental means to engage the selected magazine and to insure the proper registration of the escapement actuating devices with the escapements thereof and to support them in alinement therewith. 70
8. In a typographical machine, the combination of a plurality of magazines each provided with suitable escapements, an adjustable frame, and escapement actuating devices in part carried by the frame and in part stationarily mounted, the said frame being provided with supplemental means to insure the proper registration of the escapement actuating devices carried thereby with the escapements and also with the other stationarily mounted escapement actuating devices and to support them in alinement 80 therewith. 85
9. In a typographical machine, the combination of a plurality of magazines B each provided with suitable escapements, a vertically movable frame F, escapement actuating devices carried thereby, and supplemental sustaining means connected to the frame and movable relatively thereto to engage the selected magazine when the frame is in operative relation thereto and to support it in registration therewith. 90
10. In a typographical machine, the combination of a plurality of magazines B, a raceway to receive matrices from all the magazines, a vertically movable frame F, an intermediate bridge L carried by the frame, and supplemental sustaining means connected to the frame and movable relatively thereto to engage the selected magazine and to support it in registration therewith. 100 105
11. In a linotype machine, the combination of a plurality of magazines B, a vertically movable frame F, a transversely movable frame H mounted in said frame F, and supplemental sustaining means connected to the frame H and movable relatively to the frame F to insure the proper registration of the parts in operative relation to the selected magazine and to support them in alinement therewith. 110 115
12. In a typographical machine, the combination of a plurality of magazines B, the vertically movable frame F, the transversely movable secondary frame H mounted in said frame F, and the supplemental sustaining means O relatively movable to the frame F and connected to the secondary frame H to secure the proper registration of the parts in relation to the selected magazine and to support them in alinement therewith. 120 125
13. In a linotype machine, the combination of a plurality of magazines B, the vertically movable frame F, the transversely movable secondary frame H mounted in said frame F, and the supplemental sustaining 130

means O relatively movable to the frame F and connected to the secondary frame H and provided with the hook or extended portion O¹ to engage a stationary portion of the machine and to insure the proper registration of the parts in relation to the selected magazine and to support them in alinement therewith.

In testimony whereof I hereunto set my hand this 30th day of March, 1912, in the 10 presence of two attesting witnesses.

DAVID SHERWOOD KENNEDY.
